UNITED STATES PATENT OFFICE.

HENRY G. ANTHES, OF NEW ROCHELLE, NEW YORK.

GAME.

Application filed September 19, 1922. Serial No. 589,230.

To all whom it may concern:

Be it known that I, HENRY G. ANTHES, a citizen of the United States, residing at New Rochelle, in the county of Westchester and State of New York, have invented certain new and useful Improvements in Games, of which the following is a specification, reference being had therein to the accompanying drawing.

10 This invention relates to games, and consists of a table game or game-board intended to simulate some outdoor contest between teams of players, such as cricket, or the American national game of baseball, and to 15 permit between opposing players contests involving skill, chance and amusement.

In the accompanying drawings Figure 1 is a plan view of a game apparatus embodying the present invention, and Figure 20 2 is a section on the line 2—2 of Figure 1.

The present game apparatus comprises a game adapted to be tilted so as to cause loose pieces upon the board to move around within certain confinement. The moving or 25 rolling pieces, which are preferably balls, and usually ordinary marbles so as not to be too perfect in rolling action, are in two sets representing two opposing teams of players. The players or balls of one team 30 are distributed around the field with means for confining each within certain limits, preferably by a number of shallow recesses within which the respective pieces roll. Through this field of moving players is supposed to pass a player or runner of the 35 other team, which is set into a shallow path or circuit and caused to traverse the path from end to end, the task being to have the player or runner completely traverse the 40 path without being contacted by opposing players, this requiring skill because of the arrangement of the path at a number of points in such close proximity to the bounds or recesses of the opposing players that there 45 is continual likelihood of contact, such contact representing the putting out of the runner.

The bottom board 3 or base of the apparatus should be stiff and rigid to give a substantially flat board and its upper surface may be smooth or on the other hand slightly rough to avoid too great regularity in the rolling motions of the pieces. Around the periphery is a vertical strip 4 of card-board enclosing the field and which may be decorated to represent a fence. The two front

corners are shown provided with angle pieces 5 of card-board for the reception of the thumbs in manipulating the apparatus. In the longitudinal axis, but forward of the center, is attached at the underside of the board, a pivot or rocker 6 which may be a hemisphere of rubber. In operation the rocker rests upon any surface or table 7 while the person playing the game holds 65 the board by the thumb pieces 5 tipping and tilting it as desired to cause his marble or player to traverse the required path.

On top of the base-board is shown a layer 8 of card-board, firmly secured in contact 70 with the base, and cut away at a number of points to produce recesses and a path.

Although the principles might be used for other games, the game of baseball, as before stated, is illustrated in the present 75 example of this invention. Each of the contestants is provided with a set of marbles, the side which is out having nine marbles each marked 9 on the drawings and the side which is having its inning having 80 an equal number of marbles marked 10.

It will be convenient first to describe the path of travel of each of the players or runners of the team having its inning. A player or marble 10 is shown just beyond 85 the home-plate 11 in the shallow run-way or groove 12 leading to the first base 13. The path turns at this point extending along the groove 14 to second base 15 and thence along groove 16 to third base 17 and by 90 groove 18 to home-plate 11. The board will be tilted to cause the runner to pass around this path, and if he has successfully done so without the player being put out by contact with any opposing player, the runner will 95 be rolled onwardly along run-way 19 to the enclosure 20 reserved for players that have scored runs. This enclosure is produced by a wall 21 extending diagonally from the front to the side peripheral walls. In Figure 100 1 the wall 21 is shown broken away in section to indicate a door-way 22 by which the marble passes from the run-way 19 into the enclosure 20. Another similar enclosure 23 is arranged at the opposite side by means 105 of a diagonal wall 24 within which lie the marbles or players of the contestant who is having his innings. The two walls, 21 and 24, may be ornamented to represent grandstands and the front wall 4 between them may be indicated as a back-stop.

116 The path 12—18 of the runner passes

in close proximity to the recesses of the opposing team at a number of points marked 25 which may be considered as danger or contact points. The sides of the path of 5 the runner are quite low, being merely the thickness of the card-board 8, and the ball 10 can overhang at either side as will be understood from Figure 2. Wherever the path comes quite close to the recesses to be 10 described, the ball 10 is able to contact with a ball 9 and this is the contact which has to be guarded against in tilting the board to cause the runner to pass around the circuit. The player representing the catcher 15 is freely movable within the limitations of a recess 26 which approaches very closely to the path of the runner at a danger point 25. The pitcher is in an analogous recess 27 with an extended danger point so that 20 the runner is liable to be put out by the pitcher during substantially a quarter of the entire distance. The recesses for the different players are shown of different shapes and sizes and may of course be variously modified to increase or decrease the 25 difficulty of the game. The short-stop is shown located in a simple curved recess 28. The respective basemen are in recesses 29, 30 and 31 and the fielders in recesses 32, 33 30 and 34. The entire board is thus divided up into two levels. The higher level, the top side of the pasteboard 8, represents the field and may be colored green as representing grass, while the various depressed portions, the recesses and the path, may be 35 brown.

The game may be played by rules, and one convenient system may be as follows: The opponents may have marbles of different colors, for example, red and blue. The 40 side that shall have first inning may be decided by the toss of a coin. The side winning the toss, for example the reds, places all nine marbles in the enclosure 23 while the contestant playing the blues will place 45 the nine blue marbles in the nine enclosures or recesses 26 to 34 where each marble will roll freely as the board is tilted. If any of the blue players should slip out of 50 its enclosure during the inning the contestant will immediately replace it. The contestant having the reds will remove one marble from enclosure 23 and place it in run-way 12 just beyond home-plate, as 55 shown in Figure 1. From this point on the manipulation will be by tilting, and the object is for the red contestant to cause the red marble to roll down the run-way 12 to first base, thence along the continuation of 60 the path to second and third bases and finally to the home-plate and along path 19 to the enclosure 3. While he is endeavoring to do this the nine blue marbles are in constant motion giving a natural appearance 65 of activity and the tilting motions produces

a tendency to bring the red player into contact with one or more of the blue players namely at one or more of the danger points 25. Immediately upon the runner or red marble being contacted by a blue marble the 70 blue contestant may lift the red marble from the board as being "out." The game proceeds, the player having the inning making as many complete runs as possible and the other extracting the players which have 75 been put out, until three players have been put out, whereupon the side is declared out and the contestants change places. This will be repeated until each side has had nine 80 innings as in our national game. If desired, a third person may be engaged as 85 umpire to judge whether a player has been put out and effect the removal of the player so put out. If a player making a run shall leave the path or groove, for example the 85 run-way 12, I prefer that he should be allowed to manipulate the board to bring the runner again into the path 12 and continue 90 his run, any contact by an opening player, however, of course putting him out. It 95 might be made conditional that the runner must be rolled back into place in the run-way before the opposing contestant can touch it by hand, which would be the equivalent of putting the runner out. The nine 100 marbles of each contestant might be numbered from 1 to 9 and the contestant compelled to play them in order so that he would not be able to obtain undue advantage by reason of differences in the irregular 105 surfaces of his several marbles. It will thus be seen that I have described a table 110 game or game board embodying the present invention and enabling a contest to be carried on of the nature referred to. Many 115 matters of design, arrangement and detail may be variously modified without departing from the principles involved and therefore it is not intended to limit the invention 120 except in so far as specified in the appended 110 claims.

What is claimed is:

1. A game comprising a tiltable board 125 constructed with a shallow runway for a rolling member of one team, extending 115 around a circuit, the depth of the runway and the diameter of the member being so related that the member may substantially overhang the edge of the runway, and a 120 number of correspondingly shallow recesses for similar rolling members of the opposing team, each recess closely contiguous to the runway but separated by a low wall bounding the runway and recess, whereby the 125 members may mutually contact by their overhang across such wall, as the first member traverses such circuit.

2. A game board according to claim 1 and 130 wherein one or more of the recesses are constructed of substantial area in two dimen-

sions so that the player therein may roll freely in any direction.

3. A baseball game board according to claim 1 and wherein the runway extends about the diamond from base to base, with recesses for the basemen and other recesses for the fielders all substantially tangent to the runway but separated by such low wall.

4. A game according to claim 1 and wherein the runway and recesses are formed 10 by cut away portions in a card or sheet mounted upon a rigid base.

In testimony whereof, I have affixed my signature hereto.

HENRY G. ANTHES.
